UNITED STATES PATENT OFFICE.

GREENLEAF WHITTIER PICKARD, OF AMESBURY, MASSACHUSETTS, ASSIGNOR TO
WIRELESS SPECIALTY APPARATUS COMPANY, OF BOSTON, MASSACHUSETTS, A
CORPORATION OF NEW YORK.

RADIO TELEGRAPHY AND TELEPHONY RECEIVER.

1,224,499.

Specification of Letters Patent.

Patented May 1, 1917.

Application filed April 17, 1914, Serial No. 832,591. Renewed March 13, 1917. Serial No. 154,560.

To all whom it may concern:

Be it known that I, GREENLEAF WHITTIER PICKARD, a citizen of the United States of America, and a resident of the town of Amesbury, State of Massachusetts, have invented certain new and useful Improvements in Radio Telegraphy and Telephony Receivers, the principles of which are set forth in the following specification and accompanying drawings, which disclose the form of the invention which I now consider to be the best of the various forms in which the principles of the invention may be embodied.

This invention relates to improvements in receiving apparatus for radio telegraphy and telephony, and consists of the apparatus and arrangements thereof disclosed herein, the object of the invention being to provide simplified and more efficient apparatus.

Of the drawings, which are largely diagrammatic, Figure 1 shows an arrangement wherein the second coil C has only one side connected to the receiving apparatus D, T, which may be grounded, as shown; Fig. 2 shows a like arrangement, save that the coupling between antenna A and coil B is made inductively, by way of coil B₁, instead of directly and conductively as in Fig. 1; Fig. 3 shows an arrangement similar to that of Fig. 1, save that instead of one coil B as in Fig. 1, two coils B and B¹ are employed, so wound and connected that their corresponding ends are of opposite polarity, as indicated by the signs at their left ends; Fig. 4 shows an arrangement similar to Figs. 3 and 1, save that the coupling between antenna A and coils B and B¹ is made inductively, by way of coils B₁ and B¹, as in the case of B₁, Fig. 2; Figs. 5 and 6 show modifications of the arrangement of Fig. 3, that of Fig. 5 being a direct or conductive antenna coupling and that of Fig. 6 being an inductive coupling by way of coil B₁; and Fig. 7 is a modification involving the combination of an adjustable conducting bridge E connecting coils B¹ and B².

In each of the figures, A represents any ordinary or suitable antenna or aerial, G a ground connection or a suitable substitute or equivalent thereof, T a suitable indicator as an ordinary electromagnetic telephone re-

ceiver, and D a suitable detector, as one of the crystal rectifier or gas rectifier types. Also K represents any suitable electrical condenser, the arrow indicating adjustability of the capacity thereof. In all the figures, the double arrows indicate variability of coupling between the coils shown adjacent to such arrows; and the single arrows at the ends of leads indicate adjustability of the inductances at which the arrows are directed.

In Fig. 1 coil B is a coil of sufficient length to cause its natural period to be equal to the shortest desired wave-length. As shown, only a small portion of this coil is included in the connection A—G, and this is variable as shown, to permit adjustment of said connection A—G to the periodicity of the waves from the distant transmitter. The coil C is adapted to slide inside coil B as shown (or outside), and consists of only a few turns of coarse or flat wire, its natural period being much smaller than the shortest desired wave-length. The variation of coupling between coils B and C causes a variation of the natural period of the left hand part of coil B which is not included in the connection A—G.

The arrangement of Fig. 2 differs from Fig. 1 chiefly in the inductive coupling represented as by way of coil B₁. In this case, however, the tuning of the connection A—G to the waves is effected by the operation of adjustable condenser K.

The arrangement of Fig. 3, comprises, in addition to the parts described above, two coils C, C¹ instead of the single coil C of Fig. 1, each of the pair coöperating with its corresponding coil B, B¹, the detector D being connected between the left hand ends of coils C, C¹. By the coupling adjustments indicated by the double arrows, the natural period of the system B, B¹, C, C¹ may be made to correspond to any desired wavelength. An adjustable connection A¹ is provided for the second coil B¹, so that it, as well as coil B, may be varied as to their portions included in the connection A—G.

In the arrangement of Fig. 4, which is similar to that of Fig. 3 in the respects first above stated, the two coils B, B¹ have their right hand ends connected by a lead A²,

the coils B_1 and B'_1 providing the inductive coupling with coils B and B'_1 . As in the other figures, the left hand ends of coil B , B'_1 are open circuited, as are the right hand 5 ends, adjacent to them, of the coils C , C'_1 .

In Fig. 5, the long coil B , B'_1 has a few turns at or about the center connected, by way of the variable connections, in the connection A—G. Observe the positive and 10 negative signs. This is as if coils B , B'_1 in Figs. 3 and 4 were placed back to back, in respect of their right hand ends. Coils 15 C , C'_1 are arranged, as in Figs. 3 and 4, one adjacent to a positive end of the long coil, and the other adjacent to the negative end. The arrangement of Fig. 6 is like that of Fig. 5, save that the inductive coupling is employed, by way of coil B_1 as in Fig. 4, and the connection A—G is tuned by variable 20 condenser K as in Figs. 2 and 4 where the inductive coupling is employed.

In the arrangement of Fig. 7 the long coils B^1 , B^2 are connected to antenna coil B in any suitable way, as electrostatically 25 by way of condensers K and K^1 respectively. Coils C, C^1 and intermediates D, T are arranged, as before, at the free or open ends of coils B^1 , B^2 respectively. The proper 30 adjustments are obtained here not only by varying the coupling between C, C^1 and B^1 , B^2 , but by the movement to left or right of the conducting bridge indicated at E which connects coils B^1 and B^2 to form a potential node.

35 The arrangements of Figs. 2—7 inclusive embody all desired or necessary features of the arrangement of Fig. 1 as described and shown.

I claim:—

1. In a radio receiving system, the combination with a coil, of sufficient length to permit its natural period to be substantially equal to the shortest desired wave length, of a second coil, consisting of a few turns and having a natural period much smaller 45 than the shortest desired wave-length, said coils being open-circuited and having their free ends substantially facing one another, and the coils being bodily movable with reference to one another; the second coil 50 having unilaterally connected to it suitable means for indicating the received intelligence, substantially as and for the purpose described.

2. In a radio receiving system, the combination with two coils, of sufficient length to permit the natural period thereof to be substantially equal to the shortest desired wave length, of a second pair of coils, consisting of a few turns and having a natural 60 period much smaller than the shortest desired wave-length, each pair of coils being open-circuited, and the first pair of coils being so wound and connected that their free ends are of opposite polarity; the second 65 pair of coils being arranged in coöperative relation with the first pair and being movable relative thereto and having unilaterally connected to them suitable means for indicating the received intelligence, substantially 70 as and for the purpose described.

GREENLEAF WHITTIER PICKARD.

In presence of—

M. C. HANNON,
W. J. BARKLEY.
